UNITED STATES PATENT OFFICE.

WILLIAM H. RUSSELL, OF NEWCASTLE, CANADA.

ELECTRIC-CAR TROLLEY.

SPECIFICATION forming part of Letters Patent No. 564,395, dated July 21, 1896.

Application filed October 31, 1895. Serial No. 567,474. (No model.)

To all whom it may concern:

Be it known that I, WILLIAM H. RUSSELL, of Newcastle, in the Province of New Brunswick and Dominion of Canada, have invented 5 certain new and useful Improvements in Electric-Car Trolleys; and I do hereby declare that the following is a full, clear, and exact description of the same, reference being had to the accompanying drawings, forming a 10 part hereof.

My invention, which will be hereinafter fully set forth and claimed, relates to trolley-wheels for overhead wires for electric cars.

The object of my invention is a trolley-wheel carrier or bearing that shall make the 15 wheel less liable to be thrown off the wire.

Figure 1 is a side elevation of my improved trolley, shown on the trolley-arm. Fig. 2 is a front view of the same without the trolley- 20 arm and without guard. Fig. 3 is a rear view of the same. Fig. 4 is a vertical section of the same through the center parallel to Figs. 2 and 3. Fig. 5 is a vertical section of the same through the center parallel to Fig. 1. 25 Fig. 6 is a transverse section of the same on line 6 6, Figs. 2 and 3; and Fig. 7 is a top view of the guard, taken approximately at a right angle to the trolley-arm.

A frame of three parallel tubular bearings, 30 a small one, A, on each side and a thicker and longer one, A', in the center, is formed by connecting them rigidly by two cross-pieces A'', one at each end of the short tubes, allowing the long one to project below. To 35 this frame is rigidly secured a hub B by means of a plate b integrally formed therewith, and which is bolted or screwed to the lower cross-piece A'' and to two intermediate cross-pieces A'''; said hub forming a socket 40 for convenience of attachment of the frame to the end of the trolley-arm T. A wheel-fork is formed of a cross-head C with two tines or arms C', in which the trolley-wheel W is journaled. Said cross-head projects beyond the tines to form two lugs c, thickened 45 to form hubs, into each of which is secured, by screwing and a lock-nut d, or in some other convenient manner, a round slide-rod D, adapted to slide freely in one of the two 50 tubular bearings A. In the center of the cross-head C another hub c' is provided, into which is secured, in a similar manner with

lock-nut d, a central slide D', adapted to slide freely in the central tubular bearing A'. This central rod is of the same thickness as the 55 side rods, although the bore of the central tube is larger, but it is longer, to suit the greater length of the bearing. Upon said central slide-rod is coiled a spiral spring D'', abutting at the upper end against the lock-nut d and at the lower end against a collar a', secured to the end of the bearing A' and having a bore reduced to the diameter of the slide-rod D', for which it forms a bearing or guide. A collar or lock-nut d' is secured upon 60 the lower end of said central slide-rod D' to prevent said rod leaving its bearing.

It will be seen that the spring D'' extends into the barrel or central tube A and controls the position of the fork C C' relatively 70 to the frame A A' A'', which is fast on the trolley-arm T, causing the fork to slide freely on the frame and forming a yielding or elastic connection between frame and fork, and thus between arm and wheel. This elastic 75 connection will prevent, or at least largely help to prevent, the wheel W leaving the conductor W'.

To bridge over the angle between the trolley-arm T and the arms C' of the wheel-fork, 80 or rather the wheel W, a guard G is provided, as shown in Figs. 1 and 7. This is a light rod having one end g forked and the fork ends pivoted to a sleeve or clip G', placed upon the trolley-arm and the other end formed 85 into a long hook g'', adapted to hook and slide upon a bail G'', which is rigidly secured to the fork-arms C' in an upwardly and forwardly slanting position. Should the trolley leave the conductor W' and run against a 90 cross-wire, the guard G will cause the latter to slide over the wheel W and prevent it entering the angle formed by the trolley-arm and the bearing A B C and wheel W, while the hook g'', sliding upon the bail G'', will 95 allow the guard G to yield with the spring-bearing.

I claim as my invention—

1. The combination with a trolley-arm of a frame rigidly connected with said arm and consisting of three tubular bearings connected by cross-pieces, a fork consisting of a cross-head having arms or tines in which the wheel is journaled and three slide-rods 100

adapted to slide in the tubular bearings, a spring coiled upon the central rod and passing into the central bearing of larger bore and greater length, a collar at the end of said 5 central bearing forming a bearing for the rod and stop for the spring, a trolley-wheel journaled in the arms or tines of the fork, a guard-rod forked at one end and hooked slid-
10 ingly at the other, a sleeve or clip upon the trolley-arm to which the forked end of the guard-rod is pivoted and a bail rigidly se-
cured to the arms of the wheel-bearing pass-
ing around the trolley-wheel in front and 15 supporting the hooked end of the guard, sub-
stantially as set forth.

2. The combination with the trolley-arm of a frame rigidly connected with said arm and consisting of three tubular bearings connected by cross-pieces, a fork consisting of a 20 cross-head having arms or tines in which the wheel is journaled and three slide-rods adapted to slide in the tubular bearings, a spring coiled upon the central rod and passing into the central bearing of larger bore 25 and greater length, a collar at the end of said central bearing forming a bearing for the rod and stop for the spring, and a trolley-wheel journaled in the arms or tines of the fork, substantially as set forth.

3. The combination of two parallel slide-
bearings connected by cross-pieces, a spring-
barrel between said bearings, a hub or socket

secured to said barrel and bearings adapted for connection with the trolley-arm, a slide-rod in the barrel and each side bearing, a 35 cross-head to which said rods are secured and which carries arms for the trolley-wheel bear-
ings, a spring coiled upon the slide-rod in the central barrel and a collar at the end of 40 said barrel forming a stop for said spring and a bearing for said slide, substantially as set forth.

4. The combination of a frame consisting of parallel tubular bearings rigidly connected transversely, a spring-barrel between said 45 bearings, means of connecting said frame to the trolley-arm, a cross-head having rods slidingly supported in the tubular bearings, a central rod on said cross-head passing into the spring-barrel, a spring upon said central 50 rod bearing against a tubular collar at the end of the spring-barrel, means of contact with the conductor on said cross-head a sleeve or clip on the trolley-arm, a guard-rod piv-
oted to said sleeve or clip and means of sup- 55 porting the upper end of said guard-rod in line with the contact-piece substantially as set forth.

In testimony whereof I have signed in the presence of the undersigned witnesses.

WILLIAM H. RUSSELL.
